UNITED STATES PATENT OFFICE.

ROBERT C. SCHENCK, OF DAYTON, OHIO.

DESIGN FOR A HAND-WHEEL RIM.

SPECIFICATION forming part of Design No. 24,014, dated February 5, 1895.

Application filed November 28, 1894. Serial No. 530,276. Term of patent 14 years.

To all whom it may concern:

Be it known that I, ROBERT C. SCHENCK, a citizen of the United States, residing at Dayton, in the county of Montgomery and State 5 of Ohio, have invented and produced a new and original Design for Hand-Wheel Rims, of which the following is a specification, reference being had to the accompanying drawings, showing the same.

10 In the drawings Figure 1 is a plan view of my hand wheel rim, and Fig. 2 is a side elevation of the same.

The leading feature of my design consists in the circular rim provided with oblong slots 15 through it from top to bottom, said slots extending, with separating partitions, entirely around said rim, there being depressions or indentations in the outer and inner sides of the rim, opposite the separating partitions of 20 the slots, thus causing the rim to have a novel and pleasing appearance, both when viewed in plan and side elevation, the said slots and

depressions or indentations giving to the rim, when shown in plan, the appearance of a series of connected chain links, and when seen 25 in elevation the top and bottom of the rim have a corrugated appearance, as shown in Fig. 2.

A is the rim and a the oblong slots formed through it from top to bottom and extending, 30 with separating partitions b, entirely around said rim, while opposite said partitions, on the inner and outer surfaces of the rim, are depressions or indentations, c, this configuration presenting to the eye a pleasing appearance, 35 when viewed either in plan or side elevation.

Having thus described my design, what I claim is—

The design for the rim of hand-wheels, substantially as shown and described.

ROBERT C. SCHENCK.
